CLAIM

We claim the ornamental design for a “firearm with magazine,” as shown and described.

DESCRIPTION

FIG. 1 is a front perspective view of a “firearm with magazine” according to the present invention;

FIG. 2 is a first side view of the “firearm with magazine” according to the present invention;

FIG. 3 is a second side view of the “firearm with magazine” according to the present invention;

FIG. 4 is a front or muzzle view of the “firearm with magazine” according to the present invention;

FIG. 5 is a backside view of the “firearm with magazine” according to the present invention;

FIG. 6 is a bottom view of the “firearm with magazine” according to the present invention; and,

FIG. 7 is a top view of the “firearm with magazine” according to the present invention.

The broken lines in the drawings are used to illustrate unclaimed portions of the invention and form no part of the claimed design.

1 Claim, 5 Drawing Sheets
